UNITED STATES PATENT OFFICE.

JAMES T. MILLIGAN, OF DU QUOIN, ILLINOIS.

IMPROVEMENT IN STEAM WATER-ELEVATORS.

Specification forming part of Letters Patent No. 129,977, dated July 30, 1872.

Specification describing a certain Improved Steam-Pump, invented by JAMES T. MILLIGAN, of Du Quoin, in the county of Perry and State of Illinois.

This invention relates to the class of steam-pumps known as siphon-pumps. My invention consists in certain improvements in steam-pumps, hereinafter more fully set forth.

The drawing shows my improvement in axial section through the steam-chamber and jet, with parts above in elevation.

A is the suction-pipe, having a tapering throat, B, and a nozzle, C, of cylindrical form, upon the inside, and the end portion *c*, of tapering form, upon the outside. D is the steam-pipe communicating with the steam-chamber E that surrounds the nozzle. F is a pipe, screw-threaded at both ends, and screwing into the steam-chamber and the discharge-pipe G. The lower end of the pipe F (which screws into the steam-chamber) has a mouth, H, flaring upon the inside, having a similar upward taper to the end *c* of the nozzle, so that, as the pipe F is screwed inward and outward in the steam-chamber, the annular jet-passage I will be reduced or enlarged. K is a polygonal collar of the pipe F, to which a wrench may be applied to turn the pipe. L are the jam-nuts screwing against the shoulders of the

steam-chamber and discharge-pipe. *c'* and *h* are valve-seats of the nozzle *c* and adjusting-pipe F, respectively, by which the steam-jet may be closed when desired.

The operation is as follows: The steam passes through the steam-pipe D into the valve-chamber E, and through the annular jet-passage into the adjusting-pipe F, and forces the water forward from the suction-pipe to the discharge-pipe.

This pump may be applied to forcing a furnace-blast or forcing air for purposes of ventilation by removing the suction water-pipe.

I claim as my invention—

1. The combination of annular steam-jet I, provided with valve and seat *c'* *h*, central water-nozzle *c*, and tapering throat B, constructed substantially as set forth.

2. A suction-pipe, A, with contracted nozzle C, in combination with an adjustable pipe, F, with a bore corresponding in diameter with the bore of the contracted part of the suction-pipe, said parts being arranged to operate in the manner herein set forth.

JAS. T. MILLIGAN.
